J. A. JONES.
METALLIC WINDOW SASH.
APPLICATION FILED OCT. 26, 1912.

1,161,316.

Patented Nov. 23, 1915.

UNITED STATES PATENT OFFICE.

JOHN A. JONES, OF CINCINNATI, OHIO, ASSIGNOR OF TWO-NINTHS TO FRANK G. JONES,
TWO-NINTHS TO ARTHUR A. JONES, AND ONE-NINTH TO LUCRETIA J. PACKARD, ALL
OF CINCINNATI, OHIO, AND ONE-NINTH TO ANNA A. KING, OF BOYNTON, FLORIDA.

METALLIC WINDOW-SASH.

1,161,316.

Specification of Letters Patent. Patented Nov. 23, 1915.

Application filed October 26, 1912. Serial No. 727,836.

To all whom it may concern:

Be it known that I, JOHN A. JONES, a citizen of the United States of America, and resident of Cincinnati, county of Hamilton, 5 and State of Ohio, have invented certain new and useful Improvements in Metallic Window-Sashes, of which the following is a specification.

This invention relates to metallic frames, 10 such for example as window sashes, and particularly to frames which are formed of separate intersecting members.

An object of this invention is to produce 15 new and improved means for securing or positively locking the separate members together.

This and other objects I attain by the means herein described, and illustrated in the drawings accompanying and forming a 20 part of this application.

In the drawings Figure 1 is a fragmental perspective view of a frame embodying my invention. Fig. 2 is a fragmental perspective view of two intersecting members locked together by means embodying my invention. Fig. 3 is a fragmental perspective view, of intersecting members, and shows a tongue, which forms a detail of my invention, in the position it occupies during 25 the operation of assembling the members. Fig. 4 is a fragmental perspective view of a slotted member on which a tongue is formed and which forms a detail of my invention. Fig. 5 is a fragmental perspective view of 30 a notched member which co-operates with the slotted member shown in Fig. 4. Fig. 6 is a fragmental perspective view of the members shown in Figs. 4 and 5 in positions they occupy during the assembling operation, prior to securing them together. Figs. 35 6, 3, and 2, respectively, illustrate three successive steps in the operation of assembling and securing two intersecting members together in accordance with my invention.

In carrying out my invention I provide a slot in one member through which the co-operating intersecting member is inserted and in which it is locked by means of a tongue which projects partially across the 40 slot.

In the drawings I have shown my invention as applied to T-bars, but I desire it to be understood that the invention may be employed, with equal success, with channel

irons, angle irons or other standard sections 55 and that I do not limit myself to sections of any form or shape.

As illustrated, the web 8 of one member, which for convenience of description I will term the vertical member 9, is provided with 60 a slot 11 and a tongue 12, which, as shown, is struck from the metal of the web and is so formed that it projects partially across the slot 11, but is capable of being bent at an angle to the web 8 for the purpose of uncov- 65 ering or clearing the passage through the slot.

The co-operating member, which for convenience of description I will term the horizontal member 13, is adapted to project 70 through the slot 11, in the member 9, and is notched at 14 and 15, as illustrated in Fig. 5. The notch 14 is formed in the edge of the web portion 16 of the member 13, for the purpose of engaging an edge of the slot 11 75 in the member 9, when the members are assembled in their normal positions, and it is substantially of the same width as the web 8. The notch 15 is formed in the head portion of the member 13, extends to the inner 80 edge of the web 16, and is adapted to receive the head portion of the member 9, when the member 13 is in the normal position with relation to the member 9.

The slot 11 is so formed that it is capable 85 of permitting the horizontal member to be passed through it when the tongue 12 is moved to the unusual position; that is, when the tongue 12 is bent at right angles to the web 8. In the illustrated embodiment this 90 is accomplished by so forming the slot 11 that it extends longitudinally of the web 8 and is provided with an off-set 17, which extends from the slot inwardly to the head portion of the member 9, and produces a 95 substantially L-shaped slot in the web, one portion 11 of which is wide and extends longitudinally of the web and the other portion 17 of which is narrow and extends transversely of the web. The off-set 17 is sub- 100 stantially the same width as the thickness of the web 16, of the member 13, and the corner or shoulder formed between it and the slot 11 is rounded for a purpose which will hereinafter be described. The length 105 of the slot 11 is a little greater than the combined width of the web 16 and the thickness of the head portion of the member 13. The

tongue 12 is so formed that it extends longitudinally of the slot 11, when it is in the normal position, and it is of such length that the distance between its free end and the opposite edge 18 of the slot 11, is substantially equal to the thickness of the web 8 of the horizontal member. 5

The operation of assembling the horizontal and vertical members is as follows: The tongue 12 is bent to a position substantially at right angles to the web 8, the horizontal member 13 is located so that it extends at right angles to the member 9 and it is then tilted so that its web 16 extends longitudinally of the slot 11 and its head portion extends at right angles to the head portion of the member 8. When in this position the member 13 is inserted through the slot 11 and is moved longitudinally of itself 10 until its notch 14 occupies a position opposite to the web 8 of the member 9, and its notch 15 is located directly opposite to the head portion of the member 9. The member 13 is then turned or tilted so that its web is 15 moved to a position at right angles to the head portion of the member 9 and into contact with the edge 18 of the slot 11. In turning the member 13 to this position the inner or severed edge of its web 16 moves into the 20 off-set 17 of the slot 11, its notch 14 moves into engagement with the upper edge of the slot 11, and the edges of its notch 15 engage the edges of the head portion of the member 9. The shoulder formed between the slot 25 11 and the off-set is rounded for the purpose of aiding in tilting the member 13 to its normal position, and the severed edge of the web 16 of the member 13 may also be notched or rounded for the purpose of causing the 30 web to more easily enter the off-set 17. After the member 13 is in the position illustrated in Fig. 3, the tongue 12 is bent inwardly or back to its normal position, so that its lateral faces are flush with the faces 35 of the web 8, and so that its free end engages the adjacent face of the web portion 16 of the member 13. This positively locks the members 9 and 13 together, since the tongue 12 prevents the member 13 from 40 being tilted in the slot 11 and the notches 14 and 15 positively engage the member 9 and it cannot be released therefrom except by tilting the member 13. 45

It will be understood that the off-set 17 50 of the slot 11 may be dispensed with by providing a notch in the severed or inner edge of the web 16 of the member 13, as shown in dotted lines, at 19 in Fig. 5. Such a notch would be of the same width as the notch 14 55 and would engage the web 8 at the inner edge of the slot 11. If desired, the joint between the two members may be so constructed that the head portion of the member 13 will rest upon the head portion of the member 8 instead of being notched out, 60 65

as illustrated. Such a construction reduces the width of the notch 14, shown in Figs. 5 and 6 to the width of the web 8 of the member 9. When this construction is employed the notch 13 must be increased in depth to accommodate the tilting operation, since the member 13 will turn about the edge of one of the flanges of its head portion during the tilting operation, instead of turning about the inner or severed edge of its web portion 16. 70 75

In forming a window sash or frame portion, with the members illustrated, each horizontal member 13 is provided with as many sets of notches 14 and 15 as there are vertical members 9 in the frame or sash; and each vertical member is provided with as many slots 11 and coöperating tongues 12 as there are horizontal members in the frame or sash. The vertical members are then located in 80 parallel relation to each other and the horizontal members are tilted relatively to the vertical members, as shown in Fig. 6 and are inserted through the slots 11 to such positions that each set of notches 14 and 15 85 is located opposite to a vertical member. Each horizontal member is then turned, relatively to the vertical members, to the position shown in Fig. 3 and the tongues 12 are 90 then bent inwardly so that their inner edges engage the webs 16 of the horizontal members, as shown in Figs. 1 and 2. This locks the members together and forms a permanent frame or sash. 95

By properly proportioning the width of 100 the notches 14 and 15 to the webs and head- portions of the member 9, and by properly proportioning the length of the tongues 12, so that they firmly press the webs, engaged by them, into contact with the edges 18 of 105 the slots 11, the joints between the horizontal and vertical members will be absolutely rigid and there will be no relative motion between the members. 110

While I have illustrated my invention in 110 connection with a metal frame or window sash, I desire it to be understood that my invention may be employed in locking any two intersecting metal members together and that various changes, substitutions, 115 omissions, additions and variations may be made in the apparatus illustrated without departing from the spirit and scope of my invention as set forth in the appended claims. 120

What I claim is:

1. In an interlocking joint for bars, a bar having an L-shaped eye therein, a single tongue formed from the material removed from said L-shaped eye, a second bar having a width substantially equal to the length of the eye of the first bar, said second bar having oppositely disposed notches leaving an unnotched portion of the bar intermediate its marginal notches, substantially equal 125 130

- to the width of the offset portion of the L-shaped eye of the first bar through which the second bar is adapted to be thrust and interlocked therewith by a partial rotation, 5 in which position it is secured by the return of the single tongue to the plane of the web.
2. In an interlocking joint for bars, a flanged bar having an L-shaped opening confined to the web portion thereof, a second bar having oppositely disposed marginal notches extended through the opening of the first bar and engaged therewith by a partial rotation, the second bar being seated against the terminal wall of the off- 10 set portion of the L-shaped opening, and means for locking the bar in its adjusted position.
- 15 3. In an interlocking joint for bars, a

flanged bar having a longitudinally disposed substantially L-shaped opening confined to 20 the web portion thereof, a second bar having oppositely disposed marginal notches extending through the opening of the first bar and interengaged in the offset portion thereof by a partial rotation, said second bar ex- 25 tends in opposite directions beyond the transverse limits of the offset portion of the opening, and means for retaining the bar in position.

In testimony whereof, I have hereunto 30 subscribed my name this 24th day of October, 1912.

JOHN A. JONES.
